US0D1049311S

(12) United States Design Patent (10) Patent No.: US D1,049,311 S
(45) Date of Patent: * Oct. 29, 2024

(54) SHOWER

(71) Applicant: Kohler Co., Kohler, WI (US)

(72) Inventors: Gregory De Swarte, Sheboygan, WI (US); Anna-Pia K. Slothower, Mill Valley, CA (US); Drew Johnson, Sheboygan, WI (US)

(73) Assignee: KOHLER CO., Kohler, WI (US)

() Term: 15 Years

(21) Appl. No.: 29/922,267

(22) Filed: Dec. 21, 2023

Related U.S. Application Data

(62) Division of application No. 29/874,875, filed on Apr. 26, 2023, now Pat. No. Des. 1,015,485, which is a division of application No. 29/799,686, filed on Jul. 15, 2021, now Pat. No. Des. 989,228.

(57) CLAIM

The ornamental design for a shower as shown and described.

DESCRIPTION

FIG. 1 is a perspective view of the claimed design;

FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The ornamental design that is claimed is shown in the drawings as solid lines and surfaces having surface shading. The broken lines in the drawings are for illustrative purposes only and form no part of the claimed design.

1 Claim, 7 Drawing Sheets
